UNITED STATES PATENT OFFICE.

WILLIAM H. POWELL, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

DYNAMO-ELECTRIC MACHINE.

1,214,067.

Specification of Letters Patent. Patented Jan. 30, 1917.

Application filed February 27, 1915. Serial No. 11,405.

To all whom it may concern:

Be it known that I, WILLIAM H. POWELL, a citizen of the United States, residing at Milwaukee, in the county of Milwaukee and 5 State of Wisconsin, have invented a certain new and useful Improvement in Dynamo-Electric Machines, of which the following is a specification.

This invention relates in general to dynamo-electric machines, and has particular 10 relation to devices for supporting brushes of dynamo-electric machines in operative position relatively to commutators and to suitable terminals or cross-connectors. 15 In dynamo-electric machines of comparatively great current capacity, commutators are often required to be of such great axial length that the ordinary type of brush-rod support, offering two bearing points for a 20 brush-rod, does not provide sufficient support for the rod and brushes. Where additional supporting arms for the brush-rod are provided in connection with the ordinary type of support, the current between the 25 commutator and that portion of the support that is electrically connected to a terminal or a cross-connector is apt to divide unevenly, due to the fact that the path through one of the supporting arms is of less resistance than that through another. With this 30 latter condition present, the supporting arm in the path of least resistance tends to grab or hog the greater portion of the load, on account of the continued decrease in resistance of this path due to heating of the 35 brushes in this path.

In accordance with this invention, a brush support of conducting material and providing more than two points of support for 40 a brush-rod is provided, the support being of such construction as to insure a proper division of the current through the supporting arms between the brushes and the cross-connector or terminal.

45 It is an object of this invention to provide a brush-rod supporting device of improved construction and affording more than two points of support for the rod.

It is a further object of this invention to 50 provide a brush-rod support of improved construction and presenting a plurality of separate electrical paths between the rod and a terminal portion of the support.

These and other objects are attained by 55 this invention, the various novel features of

which will appear from the description and drawings, disclosing one embodiment of such invention, and will be particularly pointed out in the claims.

In the drawing is shown a broken front 60 elevation, partly in section, of a dynamo-electric machine provided with a brush-rod supporting device embodying this invention.

In the drawing, the invention is shown as being applied to a dynamo-electric machine 65 having a stationary field member 11, provided with windings 12 and 13, and a rotary armature 14 having a distributed winding 15. The armature is mounted on a shaft 16 which is supported in bearings 17, and a 70 commutator 18 is held in place on the shaft 16, the segments or bars of the commutator being connected with suitable points on the winding 15 by leads 19.

A set of brushes 21 is mounted in operative 75 position relative to the commutator 18, on a brush-rod 23, which in turn is supported in position by the brush-rod support or fork 24, the latter being suitably held in place, as by being secured by bolts 25 and 80 nuts 26 to a portion of a frame or yoke 27, suitably fixed in position. The support 24 is of conducting material and is insulated from the bolts 25 by an insulating bushing 28 and from the yoke 27 by an insulating 85 washer 29. A nut 26 may also serve to hold a lead or terminal member 31 in electrical engagement with the support 24, an insulating washer 34 being used to insulate the lead 31 from the nut 26 or a bearing washer 90 associated therewith.

As shown in the drawings, the support 24 comprises a body portion 35 and a perforated vertical extension 36 therefrom, through which the bolts 25 pass to secure 95 the support in fixed position relatively to the yoke 27. The body portion 35 has side portions 37 and 38 adjacent the lower edge. The ends of the portions 37 and 38 are provided with arms 39 and 41, respectively, in 100 which the brush-rod 23 is supported and held. A third arm 42 projects from an intermediate point of the body portion and is parallel to the supporting arms 39 and 41, and also serves as a support for the brush-rod 23. The portion 37 and its arm 39 may be of approximately the same cross-sectional area as the portion 38 and its arm 41. Strengthening ribs 43 and 44 may be provided between the body portion 35 and the 110

laterally extending portions 37 and 38, respectively.

If the body portion 35 were of solid construction, the electrical path between the 5 commutator bars and the extension 36, through the brush supporting arm 42, would be of considerably less resistance than the paths through the supporting arms 39 and 41. The operating result of such a construction would be that a greater part of 10 the current would flow through the arm 42 and the immediately adjacent brushes, causing such heating of these brushes as would further lower the resistance of this path and 15 finally cause these brushes to grab practically the total current and these current-carrying parts to become unduly heated.

In accordance with this invention, the body portion 35 is of such construction as 20 to prevent these undesirable operating results. The body portion 35 may be cored or hollowed out to insure that the only electrical paths between the commutator bars and the extension 36, through the arm 42, 25 are through a portion 45 at the lower side of the body portion and a portion 47 at the upper side thereof, and through a portion 46 at the lower side of the body portion and a portion 48 at the upper side thereof, the 30 portions 45 and 46 being of approximately the same dimensions. With this construction, the electrical paths between the commutator bars and the extension 36 are such as to cause approximately equal distribution 35 of the total current between the supporting arms 39, 41 and 42, the current in the arm 42 dividing between the portions 45 and 46, and avoiding such a short path between this arm and the extension 36 as would exist if 40 the body portion 35 were of solid construction.

It will be apparent that the arms 39 and 42 form parallel circuits between the commutator bars and the portion 47, and that 45 the arms 41 and 42 form parallel paths between the commutator bars and the portions 48, and, further, that the portions 47 and 48 form parallel connections between the supporting arms 39, 41, 42 and the portion 36.

It may be considered that the parts of 50 the body portion connecting the portions 47 and 48 to the portions 37, 45 and 38, 46, respectively, constitute spaced portions forming parallel paths, or parts thereof, between the brush-supporting arms 39, 41, 42 and the terminal part 36. While the terminal or supporting portion of the brush-rod support is in the form of an extension 55 36, this portion or extension may be of any suitable dimensions which may even be reduced to practically zero, in which case the terminal connection would be made at the point of union of the portions 47, 48.

It will be apparent that, in case a greater 60 number of brush-rod supports than three are

required, the general principle of divided paths, outlined in connection with the embodiment of this invention described above, may be utilized to prevent grabbing or hogging of current by any particular group of 70 brushes.

It should be understood that it is not desired to be limited to the exact details of construction shown and described, for obvious modifications will occur to a person skilled in the art. 75

It is claimed and desired to secure by Letters Patent:

1. A brush-rod support of electrically conductive material and comprising a body portion, and rod-supporting projections therefrom, said body portion comprising spaced portions forming parallel paths in circuit with said rod-supporting projections. 80

2. A brush-rod support of electrically conductive material and comprising a body portion, and rod-supporting projections therefrom, said body portion comprising spaced portions electrically connected together at one end and electrically connected to said rod-supporting projections. 85 90

3. A brush-rod support of electrically conductive material and comprising a body portion, and rod-supporting projections therefrom greater in number than two, said body portion comprising spaced portions electrically connected together at one end, and the other end of each of said spaced portions being electrically connected to an intermediate one and an end one of said rod-supporting projections. 95 100

4. A brush-rod support of electrically conductive material and comprising a body portion, and spaced rod-supporting projections greater in number than two from said body portion, said body portion forming a plurality of separate paths between a terminal portion of said support and said spaced rod-supporting projections. 105

5. A brush-rod support of electrically conductive material and comprising a body portion, a terminal extension therefrom, and a plurality of spaced rod-supporting projections from said body portion extending in a direction opposite to said terminal extension, said body portion forming two spaced paths between said terminal extension and said rod-supporting projections. 115

6. In combination, an electrically conductive terminal member, and a brush-rod support of electrically conductive material in electrical engagement with said terminal member, said brush-rod support comprising a body portion and three spaced, rod-supporting projections therefrom and integral therewith, said body portion being cored or hollowed to form two electrical paths between said terminal member and said rod-supporting projections, and each path-form- 120 125 130

ing portion being in the electrical path through an intermediate rod-supporting projection and a projection adjacent said intermediate one.

- 5 7. In a dynamo-electric machine, a current collecting device, a plurality of brushes in operative position relative thereto, a rod on which said brushes are mounted, a support of electrically conductive material for said 10 rod and comprising a body portion, a terminal portion, and a plurality of projections greater in number than two from said body portion, said rod being mounted on and in electrical engagement with said projections, 15 and said body portion being cored or hollowed out to provide two electrically parallel paths between said rod-supporting projections and said terminal portion whereby current flowing between the commutator bars 20 and said terminal portion divides into approximately equal parts through said rod-supporting projections.

8. In a dynamo-electric machine, a current-collecting device, a plurality of brushes in operative position relative to said current-collecting device, a rod on which said brushes are mounted, an electrically conductive support for said rod comprising a terminal portion and a body portion having 30 three spaced projections, said rod being mounted on and electrically connected to said rod-supporting projections, and said body portion being cored or hollowed out to provide two separate and electrically parallel paths between said rod-supporting projections and said terminal portion whereby current between said commutator and said terminal portion may be caused to divide into three approximately equal parts 35 through said rod-supporting projections and into two approximately equal parts through the spaced path-forming portions of said body portion.

9. In a dynamo-electric machine, a commutator, a plurality of brushes disposed in operative relation to said commutator, a rod on which said brushes are mounted, and a rod support of conducting material comprising a terminal portion and a body portion, and a plurality of spaced projections greater in number than two from said body portion, said rod being supported by and electrically connected to said projections, and said body portion being cored or hollowed out to provide parallel electrical paths between said rod-supporting projections whereby the current between said commutator and said terminal portion may be approximately equally distributed through

said brushes and said rod-supporting projections.

10. In a dynamo-electric machine, a current-collecting device, a plurality of brushes bearing thereon, a rod on which said brushes are mounted, an electrically conductive support for said rod comprising a body portion and a plurality of projections greater in number than two from said body portion, said rod being mounted on and electrically connected to said projections, and said body portion being cored or hollowed out to provide two electrically parallel paths between said rod-supporting projections and a terminal portion of said support whereby current between the rod-supporting projections and the terminal portion may divide into two approximately equal parts through said path-forming portions.

11. A brush-rod support of electrically conductive material and comprising a body portion, and rod-supporting projections therefrom greater in number than two, said body portion comprising electrically separate and parallel portions electrically connected together at one end, and the other end of each of said electrically separate and parallel portions being electrically connected to a plurality of said rod-supporting projections.

12. A brush-rod support comprising a body portion, and rod-supporting projections therefrom, said body portion comprising portions forming multiple paths electrically separate in part and in circuit with said rod-supporting projections.

13. In combination, a plurality of brushes adapted to coöperate with a current-collecting device of a dynamo-electric machine, a rod on which said brushes are mounted, a brush-rod support of electrically conductive material and comprising a body portion, and spaced rod-supporting projections extending from said body portion and greater in number than two, said rod being mounted on and in electrical connection with said supporting projections, and said body portion forming a plurality of separate and electrically parallel paths for current flowing between said current-collecting device and a terminal portion of said support.

In testimony whereof, the signature of the inventor is affixed hereto in the presence of two witnesses.

WILLIAM H. POWELL.
